UNITED STATES PATENT OFFICE.

HERBERT L. JOHNSON, OF FAIRFIELD, AND EDWIN W. JOHNSON, OF BRIDGEPORT, CONNECTICUT, ASSIGNORS TO REMINGTON TYPEWRITER COMPANY, OF ILLION, NEW YORK, A CORPORATION OF NEW YORK.

TYPE-WRITING MACHINE.

1,206,714.

Specification of Letters Patent. Patented Nov. 28, 1916.

Application filed September 1, 1915. Serial No. 48,478.

To all whom it may concern:

Be it known that we, HERBERT L. JOHNSON and EDWIN W. JOHNSON, citizens of the United States, and residents, respectively, of 5 Fairfield, in the county of Fairfield and State of Connecticut, and Bridgeport, in the county of Fairfield and State of Connecticut, have invented certain new and useful Improvements in Type-Writing Machines, of 10 which the following is a specification.

Our present invention relates to universal bar mechanism for typewriting machines, and its principal object is to provide new and improved mechanism of the character 15 specified.

To the above and other ends our invention consists in the features of construction, combinations of devices, and arrangements of parts hereinafter described and particularly 20 pointed out in the claims.

While our invention was especially designed for application to the Yost No. 20 typewriting machine, and is illustrated in the drawings as applied to said machine, it 25 is to be understood that our said invention is capable of embodiment in other styles of writing machines.

In the accompanying drawings showing the preferred form of our invention, Figure 30 1 is a fragmentary front to rear vertical sectional view of a Yost No. 20 typewriting machine embodying our invention. Fig. 2 is a fragmentary vertical sectional view taken on a plane indicated by the dotted line α in Fig. 1, and looking forward. Fig. 3 is a 35 fragmentary vertical sectional view corresponding to Fig. 1 but showing the type bar support shifted and one of the type bars in printing position. Fig. 4 is a side view of 40 the universal bar mechanism and one of the type actions shown in lower case printing position. Fig. 5 is a fragmentary perspective view of the universal bar mechanism.

As shown in Figs. 1 and 2, the main frame 45 of the machine comprises side plates 1, a rear connecting cross plate 2, and top plate sections 3 and 4. Fixed at opposite sides of a depressed portion in the top of the main frame are oppositely grooved trackways 5, 50 which coöperate through anti-friction rollers 6 with the grooved bottom bar 7 of a traveling carriage which further comprises end bars or frames 8 and connecting cross bars 9. Journaled on the frames 8 is a rotary platen

10. The carriage is urged constantly left- 55 ward by a motor or spring drum (not shown) of ordinary construction and its left- ward movements are controlled by carriage feeding devices comprising a feed rack 11 mounted on arms 12 pivoted to and depend- 60 ing from lugs on the bar 7. The feed rack 11 is normally maintained in spring pressed engagement with a feed pinion 13 fixed to the upper end of a vertical shaft 14 by a cross pin 15. Near its upper end the shaft bears 65 in a stationary arm or bracket 16 while its lower end takes a bearing on a stationary pivot screw 17. A toothed escapement wheel or rack 18 is provided with a hub portion 19 which surrounds the lower end portion 70 of the shaft and is prevented from downward displacement by a circular flange or plate 14^a rigid with said shaft. The hub portion near its upper end is formed with a set of ratchet teeth 20 providing a ratchet 75 wheel or clutch member with which co- operates a gravity pawl or clutch mem- ber 21 pivoted on a sleeve 22, which is splined to the shaft 14. The con- struction is such that the sleeve 22 is 80 forced always to rotate with the shaft 14, although it may be slid up and down on the shaft. Normally the clutch members 21 and 20 are engaged so that rotary motion on the shaft 14 is transmitted through the sleeve 85 22 and clutch members to the escapement wheel 18. The sleeve 22 may be slid up- ward in the usual way to separate the clutch members, permitting the shaft 14 to rotate independently of the escapement wheel 18, 90 thus releasing the carriage. Coöoperative with the escapement wheel 18 are escape- ment dogs 23 and 24 which are supported on an arm 25 integral with and projecting rearwardly from the middle portion of a 95 rocking bar 26 provided with angularly dis- posed end portions 27 (Fig. 5), which are engaged by pivots 28 secured one at each side of the base of the frame, the bar 26 being adapted to rock on said pivots to effect an 100 operation of the escapement. The means for rocking the bar are novel, comprising essential features of our present invention and will be hereinafter described in detail.

The type actions comprise each a key le- 105 ver 29 pivoted on a rod 30 mounted on a stationary support 31 and provided with a finger key at the forward end. A link 32

connects the key lever with a sub-lever 33 pivoted on a hanger 34 secured to a segment or support 35. The sub-lever is connected by a pull link 36 with a second sub-lever or 5 driving member 37 pivoted on a rod 38 carried by a segment or support 39. A draw spring 36^a is connected at one end to the member 37 and at the other end to the link 36. Pivoted to the driving member 37 at 10 40 is a type bar 41, the forward end of which is pivotally connected to one end of a guide link 42 that is pivoted at its opposite end on a wire or rod 43 supported on a segment or support 44. The opposite or rear 15 end of each type bar is provided with a type block 45 having two types 46 and 47 and rests normally against an inking pad 48 mounted on a container 49 which is secured to the segment 39. The driving levers act 20 against pins 41^a on the type bars. The sets of type bars 41, driving levers 37 and sub-levers 33 are arranged in arcs of circles which are concentric with their supporting segments. The segments or supports 39 25 and 44 are rigidly connected at their ends by parallel cross portions or bars 50 preferably cast integral with said segments and having downward extensions or arms 51 that are pivotally connected at their lower ends 30 at 52 to arms 53 pivoted at 54 in the sides of the main frame. The arms 53 are connected by a cross rod 55 which with said levers constitute a rigid pivotally supported frame. The pivots 52 are extended inward 35 to receive the upper ends of links 56 that at their lower ends are connected to shift levers 57 pivoted at their rear ends at 58 to the sides of the base, each lever 57 being provided at its front end with a shift key 40 59. Each arm 51 is provided with an upper laterally extending stop 60 and a lower stop 61, these stops being adapted to co-operate with stationary stops 62 and 63 to limit the shifting movements of the combined segments 39, 44. Normally the upper stops 60 are maintained in contact with their co-operating stationary frame stops 62 by coiled springs 64, these springs being vertically arranged and connected at their upper 45 50 ends to the bars 50, the lower ends of said springs being looped over the rear arms or end portions 53^a of the arms 53, said portions being curved upward and rearward to form hook-like extensions. When one of 55 the shift keys 59 is depressed it operates through the associate link 56 to swing down the frame 53, 55, and lower the type action support 39, 44. This support is confined to a parallel or substantially vertical movement through the frame 53, 55 controlling the lower ends of the extensions 51, the upper portion of said support being similarly guided and controlled by links or arms 65 pivoted at 66 at their front ends to the sides 60 of the main frame and at their rear ends at 65

67 to the upper portions of the extensions 51. Normally when the parts are positioned, as in Fig. 1, the lower case types are operative; when it is desired to print in upper case characters one of the shift keys 70 59 is depressed, lowering the support 39, 44 until it is arrested by the stops 61 engaging with the stops 63, this movement of the support bringing the outer or upper case types 47 into use when the associate printing keys are actuated. The segment 35 which supports the sub-levers 33 is also shifted during the case shifting operation but its movement is forward instead of downward, in order that the downward movement of the type bar support proper may be effected without depressing the key levers or disarranging the relationship among the elements comprised in the type actions. This forward movement of the 85 segment 35 is effected in part by links 68 pivotally connected at their forward ends at 69 to the upper part of the segment 35, the rear ends of said links being pivotally connected at 70 to the extensions 51 above 90 the pivots 67. The pivots 69 project outward laterally and carry guide rollers 71 that engage in horizontal stationary guide ways 72 in the inner sides of the side plates 1. The lower middle portion of the segment 95 35 is connected by a link 73 with a central lug on the segment 39, the link 73 co-operating with the links 68 to guide and control the segment 35 and give it a movement at right angles to the shifting movement of the segments 39 and 44. 100

Secured to the segment 35 is a plate 74 having projections over which are hooked the upper ends of the key lever restoring springs 75, the lower ends of said springs being connected to the key levers. This plate participates in the back and forth shifting movements of the segment 35. A horizontal cross bar 76, fixed at its ends to the rear of the shiftable support 39, 44, carries a center guide 77 for the types, this guide being fixed to the middle of the cross bar by screws 78. Depending from the middle of the cross bar is an arm or bracket 79 on which is pivoted at 80 the inner ends of two laterally extending links 81, these links at their outer ends being pivoted to stationary lugs and co-operating to prevent lateral vibration or displacement of the shiftable type bar support. 110 115 120

Means are provided for locking the type bar support and type bars down in their lower or capital letter position, said means comprising, as illustrated in Figs. 1 and 3, an upright lever 82 pivoted at 83 to the left-hand shift lever 57, the upper end of said lever 82 being provided with a key 84 and at its lower end terminating in a hook 85 which is adapted to co-operate with a fixed abutment 86. Normally the lever 82 is main- 125 130

tained in the Fig. 1 position by a coiled spring 87 which is anchored to the lever 57 and tends to maintain a lateral stop pin 88 on the lever 82 in contact with the under edge of the lever 57. On depressing the key 84 the left-hand shift key lever is operated, shifting the parts as when the key 59 is actuated, but with the difference that as soon as the hook 85 passes below the abutment 86 the spring 87 will be overcome and the lever 82 turned on its pivot, causing the hook to engage with the bottom of the abutment 86, as in Fig. 3, to hold the parts locked down. A release or unlocking of the parts is effected by pressing down on the left-hand shift key 59.

The parts as thus far described are like, or substantially like, those found in the No. 20 Yost typewriting machine.

Our novel universal bar construction comprises a universal bar proper 89 which is of sheet metal, angular in cross section and curved to conform to the curvature of the top portion of the segmental support 39, said universal bar 89 being arranged above said segment and so that its forward edge is above the pivot rod 38 when in position to be actuated by shoulders 37^a on the driving levers 37. The universal bar 89 is so supported as that it may shift down and up when said segment is shifted, the mounting of said universal bar permitting its movement back and forward independently of movement by the segment in both case positions under actuation of the driving levers 37 when the printing keys are operated. The supports of the universal bar 89 comprise a pair of sheet metal arms 90 riveted or otherwise rigidly secured to the rear portion of the universal bar near its ends and projecting rearward therefrom, and a central arm 91 riveted to the middle of the universal bar and also projecting to the rear. The arms 90 and 91 are made separate from the universal bar 89 for convenience of manufacture but are in effect parts of said bar. The arms 90 terminate in ears which are pivotally connected at 92 to the upstanding arms of bell cranks 93, which are fulcrumed at 94 on angular brackets 95, said brackets being secured by screws 96 to the rear face of the segment 39. The other arms of the bell cranks 93 project rearward and have pivotally connected to them at 97 the upper ends of depending links 98, the lower ends of said links being pivotally connected at 99 to horizontal arms 100 fixed to and extending rearward from a transverse rock shaft 101 near its ends, said rock shaft being pivotally supported in the lower end portions of the brackets 95. At each side there is a coiled spring 102 attached at one end to one of the rocker arms 100 and at the other end to the neighboring bracket 95, the two springs serving to restore the mov-

able parts including the universal bar after actuation. The middle arm 91 terminates in a downwardly extending ear which is pivotally connected at 103 to the upstanding arm of a lever 104 provided with a hub 70 portion 105 that fits over the rock shaft 101 and is secured thereto by set screws 106, thus fixing said lever 104 to the rock shaft 101 near the middle thereof. The other arm of said lever 104 extends downward and forward and has pivotally connected to it at 107 the rear end of a link 108, said link extending forward and being pivotally connected at 109 to a bracket or arm 110 that is adjustably secured by screws 111 to the under face of the rocking bar 26, said arm 110 providing a projection rigid with said bar and extending forward and upward therefrom.

Referring to the operation of the universal bar mechanism when a printing key lever 29 is depressed it will operate through the link 32, sub-lever 33, link 36 and driving lever 37 to swing the connected type bar 41 upward and forward away from the pad 48, the driving lever near the end of the movement acting against the pin 41^a to drive the type bar through the center guide into cooperative engagement with the platen or the paper thereon, all as is well known. Just 95 prior to the engagement of the driving lever with the pin 41^a the shoulder 37^a on said lever will strike the universal bar 89 and move it rearward. As a result the bell crank levers 93 are rocked, and the vertical links 100 98 are caused to descend as are the rocker arms 100 to which they are attached, thus oscillating the rock shaft 101, further impulse being communicated to said rock shaft by the lever 104 through the arm 91. When 105 the rock shaft 101 is oscillated the horizontal link 108 is moved forward and the cross bar 26 carrying the escapement dogs 23 and 24 is caused to be rocked to swing the dogs upward, the dog 23 passing out of engagement 110 with the escapement wheel 18 and the dog 24 into engagement with said wheel. The operated position of the parts at this time is illustrated in Fig. 4. During this operation the coiled springs 102 are stretched and 115 when the key is released will operate to restore the universal bar and its connected devices to normal position, the dog 24 passing down and out of the escapement wheel 18 and the dog 23 reengaging therewith. As a 120 result of the described operations a letter space movement of the carriage is effected under the impulse of the carriage motor. When one of the shift keys 59 is actuated the set of type bars will be carried downward along with the support 39, 44, and at the same time the universal bar 89 and its connected devices will move bodily downward, the link 108 swinging about its pivotal connection 109 as a center, the pivotal point 125 130

109 remaining stationary, and the inter-relationship of the universal bar and its connected devices above the link 108 not being affected by the case shift movement. Consequently, when the printing keys are actuated subsequent to the shift, the universal bar operation will take place as heretofore described for the lower case position. The actuated position of the universal bar and connected parts when in upper case position is illustrated in Fig. 3.

In order to actuate the escapement dogs from the space bar mechanism, two arms 112 (Figs. 1 and 5) are suitably fixed to the 15 under side of the rocking bar 26 near its ends, these arms extending forward and upward and terminating in out-turned end portions 113 which underlie the spacing levers 114, so that when the space bar (not shown) 20 connecting the forward ends of these levers, is actuated, the levers 114 will swing downward and engage with the ends 113, causing a rocking of the bar 26 and a consequent actuation of the escapement dogs. The parts 25 are so proportioned that this operation only slightly affects the universal bar 89.

The back and forth movements of the universal bar 89 are easy and comparatively free from friction. The horizontal lip or 30 portion of said universal bar is sustained a short distance above the top curved surface of the segment 39 and inside the curve thereof out of contact therewith by reason of the fact that said universal bar is prevented 35 from dropping downward by its own weight around the pivots 92 by the middle pivotal support 103, which is lower than the pivotal points 92, these latter being in the same horizontal line or level with each other. The 40 downward tendency of the universal bar 89 because of gravity is met by the pivot 103 on the arm 104, said arm in effect preventing such downward movement of the universal bar. At its ends the universal bar is guided 45 under angularly bent fingers 115 which are fixed by screws 116 to the webs or cross pieces 50.

What we claim as new and desire to secure by Letters Patent, is:—

50 1. In a typewriting machine, the combination of a shiftable type bar support, type bar actions, a universal bar, three levers mounted to shift with said support, the universal bar being directly connected at or near 55 its ends to two of said levers and also connected between its ends to the outer one of said levers, escapement devices, and connections between said levers and certain of said escapement devices.

60 2. In a typewriting machine, the combination of a shiftable type bar support, type bar actions, a universal bar, three levers mounted to shift with said support, the universal bar being directly connected to one of 65 said levers near its middle and to the other

two levers near its ends, a rock shaft on said support, connections between said levers and said rock shaft, and escapement devices, certain of said devices being operative from said rock shaft.

70 3. In a typewriting machine, the combination of a shiftable type bar support, a universal bar, type bar actions operative thereon, three levers mounted to shift with said support and to which said universal bar 75 is directly pivotally connected, two of the pivotal points of connection being in the same horizontal line and the other pivotal point of connection being at a different level, and escapement devices, certain of said devices being operatively connected with said levers.

80 4. In a typewriting machine, the combination of a shiftable type bar segment, a curved universal bar, type bar connections operative 85 thereon, three levers mounted to shift with said segment and to which said universal bar is pivotally connected, two of the pivotal points of connection being in the same horizontal line and the other pivotal point of 90 connection being between the other two and below said horizontal line, and escapement devices, certain of said devices being operatively connected with said levers.

95 5. In a typewriting machine, the combination of a shiftable type bar segment, a curved universal bar, type bar connections operative thereon, three levers mounted to shift with said segment and to which said universal bar is pivotally connected, two of the 100 pivotal points of connection being in the same horizontal line and the other pivotal point of connection being between the other two and below said horizontal line, said universal bar being arranged within 105 the curve of said segment but out of contact therewith, guide fingers at the ends of said segment and overlying the end portions of said universal bar, and escapement devices, certain of said devices being operatively connected with said levers.

110 6. In a typewriting machine, the combination of a shiftable segment, levers pivotally supported and shiftable with said segment, a key operated universal bar pivotally supported by said levers, a rock shaft to which said levers are connected, a rocking bar, escapement dogs supported by said rocking bar, an escapement rack, and connections between said rock shaft and said 115 rocking bar.

120 7. In a typewriting machine, the combination of a shiftable segment, levers pivotally supported and shiftable with said segment, a key operated universal bar pivotally supported by said levers, a rock shaft to which said levers are connected, a rocking bar, escapement dogs supported by said rocking bar, an escapement rack, connections between said rock shaft and said rock- 125 shaft and said rock- 130

- ing bar, and spacing levers operative on projections from said rocking bar.
8. In a typewriting machine, the combination of a shiftable segment, two bell cranks pivotally supported and shiftable with said segment, a universal bar pivotally connected with said bell cranks, a rock shaft provided with crank arms, links connecting said bell cranks with said crank arms, and 10 escapement devices connected with said rock shaft.
9. In a typewriting machine, the combination of a shiftable segment, two bell cranks pivotally supported and shiftable with said segment, a universal bar pivotally connected with said bell cranks, a rock shaft provided with crank arms, links connecting said bell cranks with said crank arms, a lever fixed to said rock shaft and connected 20 with said universal bar, escapement devices, and connections between said lever and said escapement devices.
10. In a typewriting machine, the combination of a shiftable segment, brackets thereon, bell cranks pivoted on said brackets, a curved universal bar provided near its ends with arms which are pivotally connected with said bell cranks, a rock shaft pivoted on said brackets, crank arms on said 25 rock shaft, links connecting said bell cranks with said crank arms, a lever fixed to said rock shaft and having a pivotal connection with said universal bar, escapement devices, a rocking bar supporting part of said 30 escapement devices, and connections between said rocking bar and said rock shaft.
11. In a typewriting machine, the combination of a shiftable segment, brackets thereon, bell cranks pivoted on said brackets, a curved universal bar provided near its ends with arms which are pivotally connected with said bell cranks, a rock shaft pivoted on said brackets, crank arms on said 35 rock shaft, links connecting said bell cranks with said crank arms, a lever fixed to said rock shaft and having a pivotal connection with said universal bar, escapement devices, a rocking bar supporting part of said escapement devices, and connections between said rocking bar and said rock shaft.
12. In a typewriting machine, the combination of a shiftable segment; brackets thereon; bell cranks pivoted on said brackets; a curved universal bar provided near its ends with arms which are pivotally connected with said bell cranks; a rock shaft 55 pivoted on said brackets; crank arms on said rock shaft; links connecting said bell cranks with said crank arms; a lever fixed to said rock shaft and having a pivotal connection with said universal bar; escapement devices; a rocking bar supporting part of said escapement devices; connections between said rocking bar and said rock shaft, said connections comprising an arm extending from said rocking bar and a link connecting said last recited arm with an arm 60 of said lever; spacing bars; and extensions from said rocking bar against which said spacing bars are adapted to operate.
13. In a typewriting machine, the combination of a shiftable segment, a curved universal bar, bell cranks supported on said segment, the upright arms of said bell cranks being pivotally connected with said universal bar near its ends, a rock shaft 70 supported from said segment, crank arms on said rock shaft substantially parallel with the horizontally disposed arms of said bell cranks, links connecting said horizontally disposed arms with said crank arms, 80 springs connected with said crank arms and tending to turn said rock shaft, a centrally disposed lever fixed to said rock shaft and connected at one end to said universal bar, a link connected to the other arm of said 85 central lever, escapement devices, and a rocking bar for supporting part of said escapement devices, said rocking bar being provided with an extension to which said last named link is connected.

Signed at Bridgeport, in the county of Fairfield, and State of Connecticut, this 30th day of August A. D. 1915.
